UNITED STATES PATENT OFFICE.

CHARLES S. BOARDMAN, OF BUFFALO, NEW YORK.

REENFORCING BAR FOR CONCRETE.

Application filed December 15, 1921, Serial No. 522,499. Renewed December 8, 1926.

This invention relates to reenforcing bars for concrete and is designed particularly with the object of producing an improved bar which may be successfully rolled and which will possess additional and important advantages over the types of bars as heretofore used for concrete reenforcing.

An important and characteristic feature of my improved reenforcing bar is that it is composed of alternating portions or unit lengths of dissimilar cross-section wherein the alternation of cross-section affords the means for mechanical bonding entirely or to a substantial degree. My present invention further contemplates the production of a bar employing alternations of unit lengths of standard plain cross-section offering additional and important advantages as will hereinafter appear.

In the appended drawings wherein there are illustrated approved embodiments of the present invention, similar reference characters are employed to denote the corresponding parts in the several views wherein:

Fig. 1 is a side elevation of a bar embodying features of my invention.

Fig. 2 is a cross-sectional view on line 2—2 thereof.

Fig. 3 is a similar cross-section taken on line 3—3.

Fig. 4 is a view in side elevation illustrating a modified embodiment of my improvements.

Fig. 5 is a cross-section thereof on line 5—5.

Fig. 6 is a similar cross-section taken on line 6—6 thereof.

Fig. 7 is a view in side elevation illustrating a further modified bar made in accordance with the present invention.

Fig. 8 is a cross-sectional view thereof on line 8—8.

Fig. 9 is a cross-sectional view taken on line 9—9.

Fig. 10 is a side elevational view of a further modification.

Figs. 11 and 12 are respectively cross-sections thereof taken on lines 11—11 and 12—12.

Fig. 13 shows in side elevation another modified embodiment of my invention.

Figs. 14 and 15 are cross-sectional views

thereof taken on lines 14—14 and 15—15 respectively.

My present invention in its simplest expression contemplates the production of a rolled bar of what may be termed multiple cross-section in that it is composed of successive sections or unit lengths of dissimilar cross-sectional contour in alternating series arrangement, preferably comprising the alternation of bar lengths each of which is of plain cross-sectional contour and having plane parallel surfaces. An embodiment thereof is illustrated in Figure 1 wherein the multiple cross-sectional bar combines alternating lengths 1 and 2 of plain square and plain round cross-section, the provision for mechanical bonding being afforded by the shoulders resulting from the change in cross-section.

Reenforcing bars as commercially manufactured are largely standardized on the basis of round and square cross-sections, each possessing specific advantages and meeting individual favor. My improved bar is specially designed to possess the important advantages of both types of bar, the respective sections of which it combines. It furthermore offers the additional and important advantage of being adapted for use therewith of accessories designed for use with either type of cross-section of bar such as the various forms of supports and fastenings, for instance the commonly employed wire stamped metal fastenings used for holding the reenforcing bars in accurate position. As is readily appreciated my improved bar permits of the use of fastenings designed for either of the two cross-sections by assembling with either the square or round portions of the bar in the specific embodiment as illustrated.

The length of the respective divisions or unit-lengths of the bar having uniform cross-section may be proportioned as desired, but preferably the length of the respective units may be one or more diameters of the bar and desirably may approximate three diameters of the bar, as illustrated.

The combined cross-sections as shown, consisting of alternating unit-lengths of round and square cross-sectional contour are preferred both for the reason that these cross-sections are to a large degree stand-

ardized and owing to the circumstance that these related cross-sections give approximately the greatest difference in cross-section. Correspondingly, in the described 5 type of bar wherein the full mechanical bonding results from the change in cross-section the prescribed cross-sections produce a bar which would be more difficult to pull out of concrete than most any other two 10 cross-sections that may be selected.

The cross-sectional areas of the respective 15 unit bar lengths of dissimilar cross-section desirably are equal thereby producing a bar of substantially uniform properties as to 20 strength, tensional values, bending moment, etc., throughout its length. At the junctions of the two different cross-sections of bar additional metal may be provided in the form 25 of small fillets 4 and 5 to compromise the respective sections over the junction area 3 and gradually reducing the extended portion 30 of the bar length of one cross-section to the adjacent surface of the bar length of dissimilar cross-section. As exemplified in the 35 illustrations the fillets 4 are reducing extensions of the extending square or angular portions of the bar and the fillets 5 are similarly associated with the extending round portions and converge with the squared surfaces. 40 The multiple bar construction as illustrated in Figure 1 is essentially a deformed bar without corrugations or bosses, requiring but slight additional metal at each change of cross-section in the form of the described 45 fillets. There is thus produced a concrete reinforcing bar having a substantially uniform area of cross section providing for mechanical bonding without additional metal in the 50 form of bosses and without deformation of the bar surface.

In many of the reinforcing bars previously 55 designed and some of which have been rolled, the change in cross-section to produce the deformations for mechanical bonding 45 has been brought about by rolling the leader bar and making the reduction in the cross-section by local indentures into the bar in the final pass of rolling. This type of bar 60 has been proven to be structurally weak. First, the fibres of the metal in this change 65 of cross-section have been sheared and destroyed in the reduced area of the bar, this reduction having been made in the finishing 70 process when the bar has reached a low rolling temperature and has affected the metal by compressing the fibres, intensifying the 75 structure and making a brittle bar.

This objectional local deformation of the 80 bar surface is avoided in my improved design of bar which formatively allows of the bar being rolled to completion without impairing the physical structure of the steel. In my design of bar the change of cross-section is made by allowing the original 85 metal to flow in the form of the bar and

leaving additional metal at the change of cross-section in the form of the fillets. The resulting bar is therefore uniform both as to cross-section and physical structure of the metal throughout with increased cross-section of the metal of the same texture as the bar at the change of section or junction portion 90 of the unit bar lengths.

In Figs. 3 to 5 there is illustrated a specimen bar of my improved design modified 95 to incorporate therewith bosses or annular shoulders 6 formed at the junction of the dissimilar unit lengths of bar in lieu of the fillets of the first disclosure. In this modified form the bosses are formed to be non-projecting beyond the greatest diameter of the plain bar sections.

Figs. 6 to 8 show a further modified bar 100 of this design with the bosses 6 of a diameter exceeding the greatest projection of either bar length from the center of the bar.

A bar of comparatively greater holding power in concrete is obtained by a bar having these cross-sections alternating at regular intervals, with the additional metal in bosses placed at the junction of these two different cross-sections, making these bosses of larger diameter and using the additional metal only which would be used in the two or more corrugations of the now existing reinforcing 105 bars.

In Figs. 10 to 15 a suitable modification in the construction of my improved bar is illustrated to adapt it to be rolled by ungeared rolls with corresponding commercial advantage.

The form of bar, as illustrated in Figs. 10 to 12 inclusive, may be obtained by a rolling operation employing rolls which are not geared to accurately rotate in unison. This 110 form of bar is generally similar to the illustration of Fig. 3, but wherein, in addition, there is provided and integrally rolled on the bar at opposite sides a longitudinally extending boss or rib 7 to which the bosses 6 are 115 connected in continuity with their maximum diameters in the same cylindrical plane or 120 of corresponding projection.

The provision of the longitudinal ribs 7, which in the rolling operation will occur at 125 the division of the rolls, allows of the bar being formed by the respective rolls with unsymmetrical disposition or relative positioning of the bosses or junction areas upon the respective halves of the bar. The bar produced may, therefore, correspond to the example illustrated in Figs. 13 to 15 which is provided with the integral longitudinal rib 7 and the bosses upon the opposite sides of the center of the bar in dissimilar or non-symmetrical arrangement. As will be noted 130 this bar is of a character embodying the important features of my invention in that it is a multiple bar structure composed of alternately arranged unit lengths of dissimilar 135

contour; the latter in this instance being readable upon the cross-sectional contour of one side of the bar only for as illustrated in the cross-sectional views of Figs. 14 and 15. 5 the resulting full cross-sectional contour is substantially uniform but with the dissimilar surfaces reversely arranged. The invention may therefore be defined with particular reference to this modification as comprising 10 a bar of the multiple characteristics described having longitudinally successive elongated plane parallel surfaces the alternate surfaces being provided by forming the bar of dissimilar and plain cross-sectional contour.

The described longitudinal rib 7 in addition to its function in connection with the rolling operation adds to the tensile strength of the bar and furnishes support and anchorage for the transverse ribs both during the 20 rolling operation and in the finished bar.

I have thus produced an improved bar combining the characteristics and advantages of both the plain round and plain 25 square cross-sections and providing for mechanical bonding in a more economical manner and avoiding the important objections to deformed types of bars as heretofore produced. In addition to the described advantages it may be added that my improved bar 30 will be as effective against twisting in concrete as the commercial cold twisted square bars and, furthermore, by reason of its being a multiple of what may be termed plain sections, there are no objectionable depressions 35 therein which would hold water with danger of corrosion of bars in storage. Also, as described there is provision made for substantially increasing the mechanical bond oper- 40 atively occurring between the concrete and the bar, by reason of the change of cross-section, considered with relation to the dissimilar cross-sections of uniform cross-sectional area, so that a substantial degree of 45 bonding is effected without additional metal.

In connection with the specific embodiment of my invention as here illustrated an additional commercial advantage may be obtained with relation to the customary practice of rolling square and round bar sections of sizes or diameters giving two sets of correspondingly different areas related to the respective sections. While my bar can be rolled to include all of these areas so that it can be applied in installations based upon the round bar or square bar calculations, it offers an instrumentality for compromising the sections with relation to the sizes or bonding areas allowing for the elimination of half the number of sizes of the respective sections and with a corresponding reduction in rolls required thereby reducing the cost of manufacture.

While I have illustrated and described 65 typical embodiments of the features of my

present invention it will be understood that the same may be otherwise and further modified without departing from the scope thereof and it is therefore intended that all matter herein shall be interpreted as illustrative and not in a limiting sense. In this connection it may be added by way of further example that the longitudinal rib type bar, as illustrated in Figs. 10 to 15, conforming generally in other respects to a non-projecting boss design of Fig. 4 may in similar manner be incorporated with the type of bar illustrated in Fig. 7 having the bosses in projecting arrangement.

The term "plane" in the foregoing description and in the appended claims is employed as generally descriptive of the regular or uninterrupted surfaces of both the unit lengths of square and round cross-section in that the surface of the latter is in a cylindrical plane.

Having described my invention I claim:

1. A multiple section reenforcing bar of the character described comprising a bar having alternating unit lengths of dissimilar cross-section and formed with bosses positioned at the junction of the respective unit lengths substantially as described.

2. A reenforcing bar of the character described comprising a bar having alternating lengths of dissimilar cross-sectional contour, the change of cross-section providing for mechanical bonding, each unit length of dissimilar section having plane longitudinal parallel surfaces and said bar being formed with additional metal at the junction of the unit-lengths providing junction areas of increased cross-section.

3. A reenforcing bar of the character described comprising a bar having alternating unit lengths of dissimilar symmetrical cross-sectional contour, and having longitudinally parallel surfaces, each unit length extending longitudinally of the bar for a distance corresponding to at least the diameter thereof and said bar being provided with bosses positioned at the junction of the unit lengths substantially as described.

4. A multiple section reenforcing bar of the character described comprising a bar having longitudinally successive elongated plane parallel surfaces, the alternate surfaces being provided by forming the bar of dissimilar, symmetrical cross-sectional contour and having bosses formed at the junction of said successive surfaces, substantially as described.

5. A multiple section reenforcing bar comprising a bar having alternating unit lengths of plain square and plain round cross-section, the length of the respective units extending longitudinally of the bar a distance corresponding to at least the diameter thereof and having bosses positioned at the junction of the respective unit lengths.

6. A multiple section reinforcing bar comprising a bar having alternating unit lengths of plain square and plain round cross-section, the length of the respective units extending longitudinally of the bar a distance greater than the diameter of the bar, and said respective units having substantially

equal cross-sectional areas, bosses formed on the bar and positioned at the change of cross-section and providing junction portions of increased cross-sectional area. ¹⁰

In testimony whereof I have signed my name to this specification.

CHARLES S. BOARDMAN.
